V. D. SIMONS

PROCESS AND APPARATUS FOR REMOVING WATER AND AIR FROM PAPER MACHINE DRIERS

Filed July 15, 1920

WITNESS:

J. H. Bemis

INVENTOR.

Venning D. Simons

by Sheridan Jones, Sheridan & Smith.

ATTORNEY.

UNITED STATES PATENT OFFICE.

VENNING D. SIMONS, OF CHICAGO, ILLINOIS.

PROCESS AND APPARATUS FOR REMOVING WATER AND AIR FROM PAPER-MACHINE DRIERS.

Application filed July 15, 1920. Serial No. 396,524.

To all whom it may concern:

Be it known that I, VENNING D. SIMONS, a citizen of the United States, residing at Chicago, in the county of Cook and State 5 of Illinois, have invented certain new and useful Improvements in Processes and Apparatus for Removing Water and Air from Paper-Machine Driers, of which the following is a specification.

10 This invention relates to improvements in a process and apparatus for removing air and water from paper machine driers. The principal object of the invention is to provide a more efficient apparatus for and process of removing the air and condensation, and in particular to reduce the steam pressure ordinarily carried in the drier while increasing the capacity. A further object is to effect a reduction in the steam consumption 20 per unit of paper dried. Other objects relate to various features of construction and operation which will appear more clearly hereinafter.

25 The nature of the invention will be understood from the following specification taken with the accompanying drawings in which one form of apparatus for carrying out the process has been illustrated.

In the drawings—

30 Figure 1 shows a somewhat diagrammatic view of the entire apparatus, certain parts thereof being illustrated in section; and

35 Fig. 2 shows an enlarged side elevation of the ejector by which the air and condensation are withdrawn from the drying cylinder, a part of this device also being illustrated in section.

40 In the drawings the moisture and air removing apparatus is illustrated in connection with a paper drying chamber or cylinder 10 having an inlet conduit 11 at one end thereof adapted to receive a steam pipe 12 through which steam is introduced into the chamber 10 from the main steam supply 45 pipe 13 leading from a boiler, the pressure of the steam being preferably from 1 to 10 pounds. The opposite end wall of the drying chamber has a conduit 14 leading outwardly therefrom and communicating with a casing 15 carried by the outer end thereof. The casing has an inner chamber 16 communicating directly with the conduit 14 and another chamber 17 separated therefrom by a partition 18. An outlet pipe 20 en-

gages an aperture in the partition 18 and 55 extends therefrom through the conduit 14 into the drying chamber where it communicates with a T-connection or coupling 21. A water inlet pipe 22 extends through the outer end wall of the chamber 17 and 60 through the pipe 20 into the coupling 21 where it passes through the plug 23 mounted in the end of the coupling. The water pipe 22, after passing through the plug 23, communicates with a downwardly extending 65 pipe 24. This pipe communicates through an elbow 25 with a nozzle 26 of an ejector designated generally by the numeral 27. This ejector comprises a casing 28 in which the nozzle 26 is mounted. An outlet 29 70 opens downwardly beneath the nozzle and the interior of the casing 28 is provided with a restricted opening 30 opposite the outlet of the nozzle. The passage through the casing diverges, as shown at 31, beyond 75 the restricted opening 30 and an air vent pipe 32, open at its upper end, communicates with the divergent passage 31. The divergent passage communicates with an elbow 33 connected to the end of the casing and this elbow is 80 connected with the coupling 21, previously described, through an upwardly extending outlet pipe 34. The water which passes through the pipe 22 is conveyed downwardly through the pipe 24 and discharged 85 through the nozzle 26 at high velocity so that a suction is created in the inlet opening 29 as the stream passes through the restricted opening 30. This suction is adapted 90 to draw the air and moisture of condensation from the chamber 10, the ejector being located adjacent the bottom of the chamber, as illustrated in Fig. 1, and the air, moisture and steam then pass upwardly through the pipe 34 and are discharged through the pipe 95 15 into the chamber 17 of the casing 15.

The contents of the chamber 17 pass downwardly through the pipes 36 and 37 into a receiving tank 38. The air removed with the products of condensation is allowed to 100 escape through an upwardly extending vent pipe 39 having an automatic air valve 40 at the upper end thereof. Since the use of the ejector makes it possible to discharge the condensation and air with a greater pressure than that which exists in the drier, the steam which is carried through into the tank 38 with the discharged products may 105

be returned to the drier and utilized in doing useful work and for this purpose a pipe 41 is connected to the upper part of the tank 38 and arranged to communicate with the 5 pipe 12 through which the steam is conveyed to the drying chamber. A water discharge pipe 43 leads from the lower part of the tank 38 and communicates with a centrifugal pump 44 driven by a motor 45. This 10 pump elevates the water through the pipe 46 into a heating tank 47 where the water is heated by a steam coil 48. The steam is introduced into this coil through a pipe 49 which leads from the upper part of the receiving tank 38 through a steam trap 50 and the steam is discharged from the upper end of the coil 48 through a pipe 51. The water is discharged from the upper end of the heater 47 through the pipe 52 which connects with the inlet pipe 22, previously described. The centrifugal pump 44 creates a suitable pressure or head of water for overcoming the friction of the pipe and discharging the water through the ejector nozzle 25 with sufficient force to perform the functions of removing the moisture and air from the drying chamber. The heater serves to raise the temperature of the circulating water to a point equal to or slightly greater 30 than that of the steam in the driers, thus preventing any tendency for condensation of the steam in the driers or in the ejector and pipe connected thereto.

A portion of the water which collects in 35 the tank 38 is conveyed downwardly through a pipe 55 into a boiler feed pump 56 from which the water is conveyed to the boiler through a feed pipe 57. The feed pump is operated by steam which passes thereto 40 through a pipe 58 and the flow of steam into this pump is regulated by a valve 59. This valve is mounted on the end wall of the tank 38 and is operated by a float 60 which regulates the opening and closing of 45 the valve according to the level of the water in the receiving tank. When the water rises above a predetermined limit, the float opens the valve and causes the pump 56 to operate and thereby convey a portion of the water 50 from the tank to the boiler.

It will be understood that my improved process and apparatus are not limited except as defined by the appended claims.

I claim:

55 1. The process of removing objectionable products from a paper machine drier, which consists in passing a current of water in a channel through said drier, creating a suction by said current and thereby withdrawing 60 said products with said water, separating the water from the other discharged products, and supplying said current with the water so separated.

65 2. The process of removing objectionable products from a paper machine drier con-

taining steam, which consists in creating a suction in said drier and thereby withdrawing the air and moisture therefrom, separating any steam which may be withdrawn with said air and moisture, and returning 70 said steam to said drier.

3. The process of removing air and water from a paper machine drier, which comprises passing a current of heated water through an ejector in said drier to create a 75 suction and thereby withdrawing said air and moisture with said water, separating the air and water, heating a portion of said water and supplying said ejector with said heated water.

4. The process of extracting air and water from a paper machine drier which consists in creating a suction in a circuit having separate communications with the upper and lower parts of said drier whereby said 85 air and water are withdrawn together through said circuit.

5. In apparatus of the class described, a drying chamber, an ejector located in said chamber, means for discharging a stream of water at high velocity in said ejector to create a suction, separate means connecting said ejector with the upper and lower parts of said chamber, and means for conveying from said chamber the products discharged 95 by said ejector.

6. In apparatus of the class described, a drying chamber, an ejector located in said chamber, means for passing a stream of water through said ejector to create a suction therein, a receiving tank adapted to receive the products discharged by said ejector, and means for separately withdrawing certain of said discharged products and returning them to said drying chamber.

7. In apparatus of the class described, a drying chamber, an ejector located in said chamber, a water inlet pipe leading to said ejector, an outlet conduit leading from said ejector, a receiving tank communicating with said outlet conduit, and means for heating water withdrawn from said receiving tank and returning it through said inlet pipe to said ejector.

8. In apparatus of the class described, a drying chamber, an ejector located in said chamber, a water inlet pipe leading to said ejector, an outlet conduit leading from said ejector, a receiving tank communicating with said outlet conduit, means for heating water withdrawn from said receiving tank by steam supplied from said receiving tank, and means for conveying said heated water to said inlet pipe.

9. In apparatus of the class described, a drying chamber, an ejector located in said chamber, means for passing a stream of water through said ejector to create a suction therein, a receiving tank adapted to receive the products discharged by said 120

ejector, and means for permitting the separate withdrawal of air, steam and water from said receiving tank.

10. In apparatus of the class described, a drying chamber, an ejector located in said chamber, an inlet pipe leading to said ejector, a receiving tank, an outlet conduit leading from said ejector to said receiving tank, and means for withdrawing water from said receiving tank and discharging it into said inlet pipe with sufficient velocity to create a suction in said ejector. 30

11. In apparatus of the class described, a drying chamber, an ejector located in said chamber, an inlet pipe leading to said ejector, a receiving tank, an outlet conduit leading from said ejector to said receiving tank, means for withdrawing water from said receiving tank and discharging it into said inlet pipe with sufficient velocity to create a suction in said ejector, and means for heating the water withdrawn from said receiving tank. 35

12. In apparatus of the class described, a drying chamber, an ejector located in said

chamber, an inlet pipe leading to said ejector, a receiving tank, an outlet conduit leading from said ejector to said receiving tank, means for withdrawing water from said receiving tank and discharging it into said inlet pipe with sufficient velocity to create a suction in said ejector, and means for separating the steam discharged by said conduit and conveying it from said receiving tank to said drying chamber. 35

13. In apparatus of the class described, a drying chamber, an ejector located in said chamber, an inlet pipe leading to said ejector, a receiving tank, an outlet conduit leading from said ejector to said receiving tank, means for withdrawing water from said receiving tank and discharging it into said inlet pipe with sufficient velocity to create a suction in said ejector, and means for automatically regulating the level of the water in said receiving tank. 40

In testimony whereof, I have subscribed my name.

VENNING D. SIMONS.
